(57) **CLAIM**

The ornamental design for a china, as shown and described.

DESCRIPTION

FIG. 1 is a perspective view of a china showing my new design;

FIG. 2 is a front elevational view thereof; and,

FIG. 3 is an side elevational view, the opposite side being a mirror image thereof.

The views of the china not shown form no part of the claimed design. The broken lines depicting etching on glass surfaces, hardware and moulding represent environmental elements only and form no part of the claimed design.

1 Claim, 3 Drawing Sheets

FIG. 1

FIG. 2

FIG. 3
